UNITED STATES PATENT OFFICE.

EDMUND D. CAMPBELL, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

FLEXIBLE METALLIC CAR-ROOF.

1,164,068.

Specification of Letters Patent. Patented Dec. 14, 1915.

Application filed July 28, 1914. Serial No. 853,647.

To all whom it may concern:

Be it known that I, EDMUND D. CAMPBELL, residing at St. Louis, Missouri, and being a citizen of the United States, have invented certain new and useful Improvements in Flexible Metallic Car-Roofs, of which the following is a full, clear, and exact description, such as will enable others skilled in the art to which it appertains to make and use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings Figure 1 is a fragmentary plan view, showing a portion of the assembled roof for slightly more than one-half its width. Fig. 2 is a transverse sectional view taken through Fig. 1 to one side of the roof cap, and is partly broken away at the running board saddle to show the passage of said cap and its associated parts therethrough. Fig. 3 is an enlarged transverse sectional view of the outer portion of the roof that is shown at the left in Fig. 2, but is centrally taken, as shown by line 3—3, of Fig. 1. Fig. 4 is a fragmentary plan view of the parts shown in Fig. 3, but is broken away at the left to show the relation of the parts at the eaves in section, and is taken along line 4—4 of that figure. Fig. 5 is a sectional view taken transversely of the carline at approximately the longitudinal median of the roof. Fig. 6 is a perspective view, showing the carline approaching the eaves and being adapted to the fascia board; and Fig. 7 is a like perspective view, but showing the completed assemblage of the parts constituting the joint of contiguous roof sheets at the carline.

My present invention relates to car roofs, and it has for an object the construction of a roof which shall be composed of relatively few and simple parts, which may be either purchased in the open market in a form approximating their final shapes, or be easily manufactured with a minimum of particular preparation, and assembled without the use of skilled labor.

By virtue of the above outlined conditions, stocks of the parts may be kept at division terminals, or other points, along a railroad,

or of a system of railways, and, when necessary, repairs be readily made in a short time and by such help as is available, without returning the car to a remote point.

No interlocking seams, which seams might be forced open by tension on the roof sheets, are employed in the construction hereinafter described, and the danger of the creation of leaks is minimized, the design being such that any possible seeping of water between the roof sheets and the roof caps will be followed by an automatic discharge of the water over the eaves, through the trough-like carline without any opportunity for the water to find its way to the interior of the car.

A flexibility of the roof sheets is provided for, so that any subsequent change in the relation of the car framing members will not affect the integrity of the roof, and the portions included in the joints are yieldingly interconnected against separation, such as might ordinarily occur after a roof has been in service for a considerable period.

On railroads whose clearance diagrams reveal the necessity of a conservation of lateral space, the roof herein disclosed is especially valuable, as there is no appreciable projection beyond the sides of the car of the roof caps, and there is no requirement for projecting hoods of any kind.

In the drawings, it being understood that the construction of either side of the transverse center of the car is the same, 1 indicates the side plates and 2 the ridge pole, and located laterally between the latter and each side plate are the usual purlins 3.

The sheathing 4 of the car body may be either of the outside or inside type, the former being here shown, though in cars having certain forms of framing, particularly some kinds of steel framing, it will be frequently, though not always, desirable to use the inside sheathing. Secured to the side plate 1 is shown a fascia board or plate 5, which is illustrated as lapping both the side plate and the sheathing.

Extending across the car and adapted to be supported by and connected to side plates 1, purlins 3 and ridge pole 2, are troughlike carlines 6, which, while not restricted to a given form, are preferably produced from a rolled bar having the section illustrated in the drawings, which is a well known Carnegie shape. Obviously, a pressing may be

substituted for the bar shown, or the carline may be built up in other ways, and in modified forms to give a substantial equivalent of the bar depicted. In treating said bar to produce the carline 6, it is turned to have its horizontal web 7 lowermost and its intermediate vertical leg or flange 8 and the side flanges 9 upstanding, said leg 8 having a greater height than flanges 9. The bar 10 may be pressed cold to conform it to the contour of the roof, which in the present instance is arched, but may have any other approved outline.

Vertical leg and flanges, 8 and 9, respectively, are diagonally coped off at the eaves, and the ends of the horizontal web 7, preferably devoid of said vertical leg and flanges, are shown as extended over and bent down parallel with the fascia 5, but in some types 15 of cars may be so bent directly over the side plate. Said flanges 8 and horizontal web 7 form a water chute or discharge channel in the carline, which channel is continued over the fascia by the down turned ends of the hollow cap plate rib, later described.

Secured, as by rivets, to the horizontal web 7 of carline 6, toward the opposite ends thereof, are means for connecting the carline to the car body, such as connection plates 10, each of which has a downturned flange attached to the side plate 1, though in other types of cars variously shaped structural pieces or pressings may be used to better advantage.

Roof sheets 11, provided with flanges 12, which rise vertically to an approximate height of the flange 9, forming movable abutment walls, and are there bent downwardly and diagonally to overlap the flanges 9 of the carline, extend preferably from side to side of the car. Said flanges 12 are cut off at the eaves and the remainder of each roof sheet is bent down over the fascia 5 and nailed or otherwise secured thereto, as clearly shown in Figs. 2, 4 and 7. In some steel side framing, however, said roof sheets may be directly riveted to a side plate or other member.

As seen in Fig. 4, the edges of the parts of each roof sheet which parallel the downturned portions of the horizontal leg 7 of each carline 6, are crimped to conform to the outer corners of said leg 7 and lap said downturned portions of the latter.

Mounted upon the roof sheets 11, so as to extend transversely of the roof and to cover the proximus borders and flanges of adjacent roof sheets and the interposed carline, are roof caps 13. Where the roof sheets 11 are continuous from one car side to the other, so also are said roof caps, and they have the same curvature or outline as the roof.

Each roof cap comprises a longitudinal inverted channel-shaped housing 14 pro-

vided with a centrally located upstanding inverted U-shaped hollow rib 15, adapted to receive the vertical leg 8 of carline 6, to position said cap, and outwardly extending bottom flanges 16 adapted to lie in intimate contact with the roof sheets 11 throughout the length of both.

As best discerned in Fig. 5, a suitable clearance is established between the walls of the roof caps, the flanges of the roof sheets 75 and the carline, whereby the roof sheets 11 are capable within limits or frictionally sliding beneath the bottom flanges 16 of the roof caps 13. Thus, said roof sheets are rendered flexible and may adjust themselves to deformations produced in the framing of the car superstructure and due to the vibration of the car body.

There is a decrecence of housing 14 and the rib 15 at opposite ends of each roof cap 85, 13, and the outer extremities of each together with flanges 16 are bent down over the fascia 5, or side plate 1, as determined by the type of car to which the roof is applied. Said turned down ends are secured 90 in any suitable manner to the car body, and, in the drawings, bolts 17 are shown as the fastening means, and they pass through the said down turned portions of roof caps 13 and carlines 6, fascia board 5, side plate 1 95 and connection plate or angle 10, the nuts on said bolts firmly clamping the parts together. The roof sheets are protected at the joints throughout the entire length of the latter by the roof caps, leakage thereby being entirely 100 guarded against.

Running board saddles 18, supporting the running board 19 are located at the ridge of the car over carlines 6. The under side of the saddles 18 are preferably recessed to fit over the roof caps 13, and bolts 20, projecting through the saddles 18, roof caps 13 and the vertical leg of the carline 6 secure 105 said saddles in place.

From the foregoing it is evident that I have produced a flexible metallic roof of few parts and of simple character, and in which some of said parts may be purchased as ordinary stock material approximating 110 their finished form, and the remaining parts be constructed at a relatively slight cost. It is also obvious that the roof may be repaired without a return of the car to a distant shop, and without trained labor, large 115 shop tolls or special kits.

What I claim is:

1. In a car roof, a carline of substantially an inverted T cross section and having upstanding flanges at each side thereof, purflins secured to and beneath said carline, roof sheets over said purflins and having their edges provided with vertically extending ribs adapted to extend over the edge flanges of the carline, in combination with 125 a housing cap having a central hollow rib, 130

- portions extending outwardly and downwardly from said rib to cover said carline and the ribs on said roof sheets, and outwardly extending continuous flanges pressuring flat-wise upon said roof sheets to frictionally engage and retain said roof sheets in position.
2. In a car roof in combination, a carline having upstanding flanges at the edges thereof to constitute a trough for the conducting away of water or moisture, roof sheets having their edges provided with ridges constructed to loosely extend over said flanges, and a cover cap adapted to house said carline and the edges of said roof sheets, said cover cap being provided with a hollow ridge extending over the fascia board, said hollow ridge constituting a drip opening to conduct water from said trough.
3. In a car roof in combination, a carline having upstanding flanges at the edges thereof, a vertically extending leg at substantially the middle of said carline, said leg extending to a greater vertical height than said flanges, said flanges and said vertical leg being coped off at the ends of the carline, the web of said carline being bent downwardly and adapted to be secured through the fascia board to the framing of the car, roof sheets having their edges provided with ridges to extend over and loosely inclose the upstanding flanges of the carline, and a cover cap provided with a hollow ridge to embrace said vertical leg, continuous flanges formed at the edges of said cover cap and adapted to frictionally engage said roof sheets, said hollow ridge being extended downwardly over the end of said carline to constitute a drip opening for the troughs formed in the main portion of said carline.
4. In a car roof in combination, a carline having its edges provided with upstanding flanges, roof sheets having ridges formed on the edges thereof, said ridges being adapted to loosely engage the upstanding flanges on
- said carline, in combination with a cover cap covering said carline and said ridges and having continuous flanges extending flatwise upon said roof sheets adjacent the edges thereof to frictionally engage said roof sheets and maintain the same in predetermined relation to constitute a roof, and means at the ridge of said roof and at the vertical edges thereof for securing said cover caps in position.
5. In a car roof in combination, carlines having upstanding flanges at the edges thereof, a vertically extending leg between said flanges, purlins secured beneath said carlines, in combination with roof sheets having means at the edges thereof to loosely engage said flanges, and a cover cap provided with a hollow ridge extending over said vertical leg and outwardly extending portions covering the edges of said roof sheets together with downwardly extending portions carrying outwardly extending flanges that frictionally engage said roof sheets to maintain the same in position upon said purlins.
6. As an article of manufacture, a cover cap for a roofing seam, said cover cap being formed with a continuous upstanding rib in the middle thereof, outwardly extending portions adjacent said rib, downwardly extending walls from said outwardly extending portions, and edge flanges extending substantially at right angles to said walls.
7. As an article of manufacture, a cover cap for roof seams in railway cars, said cover cap comprising a sheet metal member having outwardly extending flanges, upwardly extending walls, inwardly extending portions, and an upwardly extending rib joining said cover portions.

In witness whereof I have hereunto set my hand in the presence of two witnesses.

EDMUND D. CAMPBELL.
